T & J Aldridge,

Smoke Consumer,

No 18,491.

Patented Oct. 27, 1857.

UNITED STATES PATENT OFFICE.

THOMAS ALDRIDGE AND JOHN ALDRIDGE, OF HUDSON, NEW JERSEY.

IMPROVEMENT IN FURNACES.

Specification forming part of Letters Patent No. 18,491, dated October 27, 1857.

To all whom it may concern:

Be it known that we, THOMAS ALDRIDGE and JOHN ALDRIDGE, of the city of Hudson, State of New Jersey, have made certain new and useful improvements in the arrangement of furnaces for burning the waste smoke and gases, and at the same time supplying such furnaces with a hot-air blast, thus rendering all such a smoke-consuming hot-air-blast furnace; and we do hereby declare that the following is a full and clear and exact description of the construction and operation of the same, reference being had to the accompanying drawings, and to the letters of reference marked thereon and making a part of this specification.

Figure 1 is a general perspective view of an ordinary boiler and furnace with our invention attached thereto, and showing how it is made self-regulating or automatic by and according to any desired pressure of the steam. Fig. 2 is a more particular view of the mechanical arrangement by which our invention is rendered self-adjusting or automatic, and which is worked by the pressure of the steam in the boiler.

The nature and objects of our invention consist in the application and use of new and improved mechanism by which the smoke and gases that generally pass off through the chimney and are lost are withdrawn from the chimney, mixed with heated atmospheric air to promote their entire combustion, and then carried to and under and consumed by the fire, thereby economizing fuel and obtaining an increased quantity of heat therefrom, and also in rendering the entire apparatus a mechanism self-regulating or automatic.

In the various methods which have been heretofore devised for burning the smoke of furnaces the effort has usually been to confine the smoke on top of the fire, thus rendering the furnace a close furnace, and consequently rendering necessary some means to facilitate combustion, retarded by the pressure of the smoke on top, and which also would check or interfere with the natural and necessary draft of the fire. These objections are obviated by our invention, while the combustion of the smoke is more complete, and the draft is rendered more uniform, and is also made self-regulating.

Its construction and operation are as follows:

A is an ordinary cylinder-boiler set in the foundation B, the chimney C being in this case represented a little at one side of the rear end of the boiler.

D is the furnace-door, and E the door to the ash-pit underneath the fire. These are constructed as usual.

To the chimney at or near the point or place at which the smoke, &c., enter it or cease to act upon the boilers, we attach or insert a tube or smoke-conductor F, the other end of which enters the ash-pit or under the fire-grate. This conductor is all close except at the ends, and may be constructed of wood or brick; but it should be constructed of materials which are the poorest conductors of heat. If made of other materials, it can be covered with any non-conductor. It may also be connected at either side of the chimney or smoke-stack, most convenient in any particular case; but it is preferable to connect it to that side opposite or nearest opposite to the fire, as then the natural current of the smoke, heat, &c., will co-operate with any mechanical means made use of to take these from the chimney. Such conductor may of course be accommodated in shape, direction, &c., to the circumstances of any particular case, though sharp turns in it should be avoided; but it should be connected with the chimney near where the smoke enters it, or when the boilers extend only a part of the distance to the chimney and there is a flue between them and the chimney, then it should be connected to such flue at or near the point where the smoke and gases cease to affect the boilers, and the other end should enter the furnace under the fire, as these are the most important requisites of its position.

To the smoke-conductor we attach a blower G, the exact location of which in the conductor is not material, except that it should be near the chimney to draw more completely the smoke, &c., from the chimney and more perfectly mix therewith the atmospheric air for the purposes hereinafter stated. Its construction is not peculiar, except that it has its discharge-opening at the side, experience having shown that when so constructed its capacity of discharge is increased. We ac-

tually, as a general thing, construct the blower with an opening on each side, so that according to location the conductor may be attached to either side of it, and so that when desired a conductor may lead from each side to a separate fire or furnace, thus at the same time supplying a hot-air blast to two or more fires. Its size should be proportioned to the amount of fuel consumed and to the size of the furnace or engine. Its action is to cause a constant suction or draft from the chimney, thus preventing the escape and loss of the smoke, &c., and forcing it in the direction of the arrow under the fire, in passing through which everything of a combustible nature is consumed, thus increasing heat and economizing fuel.

In the construction of new furnaces, or when the same can be done in altering old ones, it will be best to place that part of the conductor F between the blower and the furnace within the foundation and under the boilers and opening under the fire through the bridge-wall, so that there shall be but little, if any, loss of heat, or which does not act upon the boilers.

As is well known, the combustion of fuel, particularly coal, produces large quantities of carbonic-acid gas, to get rid of which, as it is not a supporter of combustion, has been an end much sought for. This, however, we do not so much desire to accomplish as to supply and mix therewith large quantities of heated atmospheric air to increase combustion. The union of gases being, however, a mechanical mixture rather than a chemical affinity or combination, it becomes necessary that the smoke, &c., drawn from the chimney should be effectually mixed with the atmospheric air and that this mingling should be effected before the parts are brought in contact with the fire. This we accomplish by admitting atmospheric air into the smoke-conductor near the blower or between it and the chimney, so that both together shall be subjected to the action of the blower, by which they are completely mixed, and by which, also, an abundant supply of atmospheric air is obtained. In order, however, that the fire may not be checked by the temperature of the atmospheric air, the pipe which supplies it should be so situated in respect to the fire or boilers that the air will be heated before it passes into the conductor, as above described.

In the drawings, H is the mouth of the atmospheric-air tube, and its position and its entrance into the smoke-conductor F is shown by dotted lines h h. As the quantity of atmospheric air required will of course vary somewhat, according to the kind of coal burned, the admission of the air is regulated by the slide-door I, by which the mouth of the tube H may be enlarged or diminished, as desired. The furnace and ash-pit doors should be shut tightly, so that no air can enter the furnace except from F. As above remarked, the position of the tube H or the location of

its mouth opening to the atmosphere is immaterial, it only being important that it should be so placed in respect to the fire or boiler that the air can be completely heated and that the other end connects with the smoke-conductor at or behind the blower.

As will be apparent from the foregoing description, the draft of the fire will depend upon or, rather, is produced by the blower, which forces the smoke and gases under and through the fire, and is not produced or affected to any extent by the form or height of the chimney, the expense of constructing which and lining it with fire-brick can be saved.

To render our invention automatic, we regulate the speed of the blower, and consequently the draft of the fire, by and according to any required pressure of the steam in the boiler. This we accomplish by the following arrangement: From the boiler A a steam-pipe J connects with and under a small cylinder K, which may be placed where most convenient or desirable, in which plays a piston or float having a rod L, such float being a little smaller than the cylinder, so that there shall be but little or no friction, and resting upon a strong piece of vulcanized rubber fastened between the sides and bottom flange of the cylinder, and which will from its elasticity allow all necessary movement to the float and its rod. Upon L rests the lever M, the short arm having its fulcrum at N and the long arm regulated by the weight W, so that the float will move at any desired pressure of steam in the boiler. To this long arm connects the elbow or bent lever P by means of the short bar O, the elbow P working on the pivot p, and the other end of which joints with the strap-stick a a a a, which plays between the conical pulleys Q Q', changing the position of the band b b, the links c c moving such band more certainly and quickly. These conical pulleys are placed so that the largest diameter of one shall be opposite to the smallest diameter of the other, one Q having a "fast-and-loose" pulley d, as it is called, over which plays a belt from the engine or any other power, and the other Q' working the blower G by means of a belt R. Whenever the pressure of the steam becomes greater than that required, the long arm of the lever M will rise and through the elbow P move the strap-stick a a in such a direction that the band b will be moved to a smaller diameter of Q and to a larger diameter of Q', thus decreasing the speed of the blower G, and consequently lessening the draft. When the pressure becomes too little, the lever M will fall and the band b be moved in a contrary direction by a contrary movement of the strap-stick and the speed of the blower, and consequently the draft, be increased. Thus the action of the blower and the draft is rendered automatic and is regulated wholly by the pressure of the steam, the draft increasing as the pressure of steam diminishes, and vice versa. In actual use

this mechanical arrangement is continually vibrating, thus evidencing its sensitiveness and accuracy. In the drawings the strap-stick and pulleys are represented as supported by the standards *f f f f*; but they will be usually supported from some part of the building overhead.

The practical operation of our invention will be best illustrated from the following facts: We constantly keep the damper of our chimney almost entirely closed, nor is dense smoke, even when burning soft coal, ever seen to rise from it.

Previous to the use of our invention the brick-work under our boilers became but moderately heated, while the chimney for some distance was made very hot, as is the case in common furnaces and chimneys; but now with its use the chimney becomes only moderately heated, while the foundation brick-work is constantly very hot, thus showing that the heat is retained and made effective where it should be—under the boilers. The temperature of the contents of the smoke-conductor near where it enters under the fire is also continually from 220° to 230°.

We are aware that "smoke-consuming furnaces," as they are called, and we use the word "smoke" in its usual and broader signification, and not in its chemical and more restricted meaning, have been arranged; but in these as a general thing, and this we believe is particularly the case in those which have proved most available, the effort has been to confine and retain by pressure or otherwise the smoke over the fire until it should be consumed. This is the case in the original and reissued patents of 1839 and 1853 of Diempfel, and also in Case and Soule's patent of 1856, and is also the substantial arrangement made use of in Woodcock's English invention and patent, which seems to be the most successful in use there. The introduction of heated atmospheric air to assist combustion of the smoke has also been used; but the object of its introduction has been to produce and keep up the necessary combus-

tion in the fire, which is of course checked and interfered with by obstructing the natural draft by means of the smoke confined on top of the fire; and by none of these plans has the combustion of the smoke been made to assist or influence the draft of the fire; nor have they been made self-regulating or automatic, both of which are united in our invention; nor can any of the most available plans, so far as we know, be attached to any ordinary boiler or furnace without material alterations for such purpose, whereas our invention can be connected to any and all without any necessity of changing their structure and at a trifling expense and with most satisfactory results. We do not therefore claim, generally, either the construction of "smoke-consuming furnaces," as they are called, or returning the smoke, gases, &c., of the fire back to or under the fire or furnace, many differently-arranged plans having been devised and used for such purpose; nor do we claim the mingling of atmospheric air with the products of combustion, as this has been effected to a greater or less degree by many inventions; but

What we claim as our invention, and desire to secure by Letters Patent, is—

1. The combination and arrangement of the smoke and gas conductor *F*, the atmospheric-air tube *H*, and the blower *G*, arranged and located substantially as and upon the principles before declared, and for the uses and purposes set forth and described.

2. In connection with such arrangement of the smoke-conductor *F* and air-tube *H*, regulating the velocity of the blower *G* by and according to the pressure of the steam in the boiler through the intervention of the conical pulleys or their equivalent, substantially as and for the purposes set forth and described.
